UNITED STATES PATENT OFFICE.

JOHN R. WOOD, OF NEWARK, NEW JERSEY, AND DANIEL CURTIS EPRIGHT, OF SPRING CITY, PENNSYLVANIA, ASSIGNORS TO THE PEERLESS FLASK AND MOLDING MACHINE COMPANY, OF NEWARK, NEW JERSEY, A CORPORATION OF NEW JERSEY.

MOLDING-MACHINE.

1,204,529.

Specification of Letters Patent. Patented Nov. 14, 1916.

Original application filed April 14, 1913, Serial No. 760,955. Divided and this application filed November 25, 1913. Serial No. 802,868.

To all whom it may concern:

Be it known that we, (1) JOHN R. WOOD and (2) DANIEL CURTIS EPRIGHT, citizens of the United States, residing at (1) Newark 5 and (2) Spring City, in the counties of (1) Essex and (2) Chester, and States of (1) New Jersey and (2) Pennsylvania, have invented a certain new and useful Improvement 10 in Molding-Machines, of which the following is a full, clear, and exact description, reference being had to the accompanying drawings.

This invention relates to molding devices and machines, being a division of our application No. 760,955, filed April 14, 1913.

It is the general purpose of this invention to provide a new and useful sand-retaining and disengaging device for molds, which device shall be convenient of operation and 20 which shall comprise simplicity of construction with efficiency of operation.

Further and more generally, the invention may be defined as consisting of the combinations of elements embodied in the claims 25 hereto annexed and illustrated in the drawings forming part hereof, wherein—

Figure 1 represents a side elevation of a molding machine such as shown, in our application aforesaid and having the sand-retaining device applied thereto; Fig. 2 is an 30 end elevation of the flask and its supporting platform; Fig. 3 a vertical sectional view through the flask, the platform being shown in elevation; Fig. 4 a detail in plan of the bottom of the cope section; and Fig. 5 a detail in section of such cope section.

Describing by reference characters the various parts illustrated herein, 1 denotes generally the base of a molding machine of the 40 "rock over" type. This base is shown as mounted on casters 2, whereby a truck is provided.

3 denotes a pair of vertical standards projecting upwardly from the central portion 45 of the base, such standards affording a pivotal support for the cope and the attached drag. The cope 4 is provided with a pair of bracket arms 5, which are preferably rigidly connected to the shaft 6, carried by the standards. Each arm 5 is provided with an

extension 7, at one side of its pivotal support, and these extensions support a rod 8 to which one end of a spring 9 is connected, the opposite end of the spring being connected to the frame 1. For the purpose of 55 limiting the rotary movement of the cope on the right-hand side of the standards 3, arms 10 are provided which project from the cope and which are adapted to engage stops 11 on the standards. 60

On one side of the standards 3 a post 12 is provided and on the opposite side of the standards there is a vertically adjustable platform 13. This platform is provided with posts 14 adapted to enter the guides 15 65 and to be engaged and operated by cams 16 on a cam-shaft 17 having an operating lever 18. To prevent the cams from being rocked by the weight of the supported parts, we provide a gravity latch consisting of a lever 70 19 which is pivoted intermediate of its ends, as indicated at 20, and which has at its lower end an arm 21 which is adapted to drop by gravity beneath the lower surface of the cam 16 when the cam shaft has been rotated a sufficient distance in a platform-elevating direction. 75

The platform 13 is provided with posts 22 which are vertically adjustable in the tubular bosses 23. 80

24 denotes an operating lever which is adapted, through mechanism forming no part of the invention of this case, to engage the posts and hold them in an adjusted position. 85

25 denotes a pair of rigid posts carried by the base and located adjacent to the standards 3, while 26 denotes a pair of posts at one end of the base 1 and pivotally supported thereby, as shown at 27. 90

Coöperating with the cope 4 is a drag 28 and the latter is shown as provided with a bottom board 29 retained in place by the latches 30 carried by the cope.

In the molding operation, it is necessary 95 to remove the match plate 31, bring the flask sections 4 and 28 into engagement, and then release the mold section which is in the cope and allow it to drop upon the top of the mold section which is within the drag. 100

The parts hereinbefore described constitute, in their details, no part of the invention which is intended to be secured in and through this application, the construction of the said parts being shown, described and claimed in our application No. 760,955 hereinbefore referred to. For the purpose of supporting the sand in the cope prior to the removal of the match-plate and of disengaging the sand after such removal, we provide the particular construction of sand-retaining and disengaging devices shown in Figs. 2 to 5 of the drawings.

The bottom of the cope 4 is provided with a flange 4* forming an extended base which carries the sand-retaining plates. Four of these plates are shown, one for each bottom face of the flange. The plates 32, in the construction illustrated herein, are mounted on opposite sides of the cope flange 4* and are each provided at opposite ends thereof with inclined projections 34. The plates 33 are also opposed to each other and are provided with inclined slots 35 adapted to receive the inclined projections 34. The plates 32 and 33 are adapted and intended to slide toward and from the interior of the cope, and for this purpose they are provided with slots 36 which receive the shanks of the headed pins 37, carried by the cope flange 4*.

For the purpose of moving the sand-retaining plates inwardly and outwardly, the following construction is provided:—38 denotes a pair of levers, each of which is shown as pivoted intermediate of its ends on a bolt 39 carried by a lug 40, said lug being formed with and projecting from the cope. One end of each lever is provided with an operating handle 41, while its opposite end is pivoted to a link 42, as indicated at 43. The opposite end of the link 42 is connected with one of the corners of the plate 33 at the opposite side of the cope from the said lever, the point of connection being indicated at 44. At the same distance from the pivot 39 as the point of connection 43, each lever 38 is also connected to a plate 32, the point of connection being indicated at 45.

Identically the same construction and connections are provided at the opposite end of the cope flange from that which carries the parts thus described, similar numerals 38—45 being employed to designate these parts.

By the construction described, it will be apparent that the plates 33 may be moved inwardly and toward the center of the cope by the lever 38 and that the outer inclined edges of the slots 35 will act upon the outer edges of the inclined projections 34 to move the plates 32 inwardly, with the result that the plates 32 and 33 will project within the

interior of the cope bottom and there provide a retaining shelf for the compacted sand, the positions of the parts at this time being shown in Figs. 1, 2, and 3. It will be evident that, by moving the lever-handles 41 in the reverse direction, the inner inclined edges of the slots 35 will engage the correspondingly inclined edges of the projections 34, as the plates 33 are moved outwardly, with the result that the sand-retaining device as a whole will be moved outwardly to clear the inner bottom edge of the cope and permit the sand to drop, the positions of the parts at that time being shown in Fig. 4.

It will be apparent that, by the construction illustrated and described herein, we have provided a sand-retaining device which is simple in construction and efficient in operation, and which may be operated from one side of the flask. Furthermore, the interengaging parts are so mounted and arranged as to minimize the danger of obstruction by sand.

Having thus described our invention, what we claim is:—

1. The combination, with a flask section, of a plate slidably supported at the bottom of such section, means connected with said plate for moving the same inwardly and outwardly, a second plate slidably supported at the bottom of said flask section, connections between said plate and the first mentioned plate whereby the second plate will be moved inwardly and outwardly by corresponding movements of the first mentioned plate, one or more additional plates slidably supported at the bottom of the flask section, and interengaging connections between the last mentioned plate or plates and the two first mentioned plates whereby such other plate or plates will be moved inwardly and outwardly by corresponding movements of the two first mentioned plates.

2. The combination, with a flask section, of a plate slidably supported at the bottom of said section, means connected with said plate for moving the same inwardly and outwardly, a second plate slidably supported at the bottom of the flask section, means connecting the last mentioned plate with the first mentioned plate whereby the last mentioned plate will be moved inwardly and outwardly with the first mentioned plate, additional plates slidably supported at the bottom of the flask section, and interengaging connections, including inclined slots and projections, between the said other plates and the first and second plates whereby all of said plates will be moved inwardly and outwardly by movements imparted to the first mentioned plate.

3. The combination, with a cope having a

bottom flange, of plates slidably mounted on opposite sides of said flange, levers connected to one of said plates and adapted to move the same inwardly and outwardly, 5 links connected with said levers and with the opposite plate for moving the same inwardly and outwardly simultaneously with the first-mentioned plate, plates mounted on the intermediate sides of the cope bottom 10 flange, and means including inclined slots and projections for connecting the last-mentioned plates with the first-mentioned plates.

4. The combination, with a cope, of plates 15 slidably mounted on opposite sides of the bottom of the cope, levers connected to one of said plates and adapted to move the same inwardly and outwardly, links connected with said levers and with the opposite plate 20 for moving the same inwardly and outwardly by the movement of the first-mentioned plate, plates mounted on the intermediate sides of the cope bottom, and means connecting the last-mentioned plates with 25 the first-mentioned plates.

5. The combination, with a flask section, 30 of a plurality of segmental plates slidably mounted on the bottom of the said flask section and adapted to be moved within the inner periphery of said bottom, means connected with one of said plates for moving the same, connections between said plate and an opposed plate whereby the last mentioned plate may also be moved inwardly 35 and outwardly as the first mentioned plate is so moved, and connections whereby the movements of the said plates will be transmitted to the remaining plates.

6. The combination, with a flask section, 40 of segmental plates slidably mounted on the bottom of the flask section and adapted to be projected inwardly beyond the inner periphery of the bottom, operating means connected with and common to two opposed 45 plates for moving the same inwardly and outwardly, and interengaging connections between said plates and the other plates.

7. The combination, with a flask section, 50 of a plurality of segmental plates mounted on the bottom of said section, means connected with one of the plates for moving the same inwardly and outwardly, a connection between said means and another plate whereby the last-mentioned plate may be 55 moved inwardly and outwardly with the first-mentioned plate, and interengaging connections, including inclined slots and projections, between all of said plates, whereby the movement of the first-mentioned plate 60 will produce a similar movement in the other plates.

8. The combination, with a flask section, 65 of plates slidably mounted on the bottom of

the flask section, levers pivoted intermediate of their ends and each connected, at one 65 side of said pivot, to one of said plates and adapted to move the same inwardly and outwardly, links connecting said levers on the opposite sides of their pivots with a plate opposite the first-mentioned plate, and 70 means connecting the said opposed plates with the intermediate plates, whereby a movement of the opposed plates will produce a corresponding movement of the intermediate plates.

9. The combination, with a flask section, 75 of a plate slidably supported at the bottom of said flask section, means whereby said plate may be moved inwardly and outwardly, a plurality of plates additional to 80 the first mentioned plate also slidably supported at the bottom of the flask section, and connections whereby the movement of the first mentioned plate may be transmitted to all of the remaining plates whereby all of 85 said plates may be moved inwardly and outwardly by like movements of the first mentioned plate.

10. The combination, with a flask section, 90 of a pair of opposed plates slidably supported at the bottom of said section, means for simultaneously moving said plates inwardly and outwardly, plates interposed between the ends of the first mentioned plates and also slidably supported at the bottom 95 of the flask section, and means connecting the last pair of plates with the first pair of plates, such connecting means comprising inclined slots formed in the end portions of the plates comprising one pair and inclined 100 projections carried by the end portions of the plates of the other pair and extending into said slots, whereby the plates comprising the second pair will be positively moved inwardly and outwardly by corresponding 105 movements of the first pair of plates through the engagement of the opposite sides of the inclined projections with the opposite sides of their respective inclined slots.

11. The combination, with a flask section, 110 of a plate slidably supported at the bottom of such flask section and movable inwardly and outwardly, a second plate slidably supported at the bottom of the flask section, 115 means connecting said plates whereby the movement of one plate will produce a like movement in the other, a plurality of additional plates also slidably supported at the bottom of the flask section, interengaging connections between the first and second 120 plates and the other plates whereby the movement of the first two plates will be transmitted to such other plates, such connections including inclined projections carried by some of said plates and inclined slots 125 in the adjacent plates receiving said projec-

tions, whereby the movement of the first two plates inwardly and outwardly will cause a corresponding movement in the other plates through the engagement of opposite sides of the slots with opposite sides of their respective inclined projections.

In testimony whereof, we hereunto affix

our signatures in the presence of two witnesses.
